UNITED STATES PATENT OFFICE.

PER ALEXANDER FAUST, OF MIAMI, ARIZONA.

TUYÈRE FOR CONVERTERS OR THE LIKE.

Application filed May 5, 1924. Serial No. 711,271.

To all whom it may concern:

Be it known that I, PER ALEXANDER FAUST, a citizen of the United States, residing at Miami, in the county of Gila and 5 State of Arizona, have invented certain new and useful Improvements in Tuyères for Converters or the like, of which the following is a specification.

The invention relates to tuyères and more 10 particularly to tuyères for converters, or similar metallurgical apparatus, which undergo periodic punching operations for the purpose of preventing the blocking up of the tuyère pipes and insuring the passage of a 15 constant stream of air or similar fluid into the charge.

More specifically, the improvement comprises special means for enabling these 20 punching operations to be performed without the dangers and disadvantages commonly attending them.

In the copper converting industry, for 25 example, each converter is equipped with from twenty to thirty tuyère pipes, to which air for the charge under from ten to fifteen pounds pressure is conducted in turn from a main and a wind-box.

Due to the comparatively low temperature 30 of the air entering the molten charge, the liquid chills at the point of contact therewith and the discharge ends of the tuyère pipes soon become blocked. To prevent this and keep a constant stream of air entering through the tuyère a punch rod is 35 introduced at frequent intervals into the charge through each of the tuyère pipes past a suitable valve located at or on the fore-wall of the tuyère box. The duration of the blow of a charge in the particular 40 converter operation referred to by way of example is about three and one-half hours, and within this period each tuyère has to be punched anywhere from fifty to one hundred times, the punch rod being inserted and 45 withdrawn completely each time.

Practical punching operation requires a punch rod having an upset end and since the tuyère pipe, which may be assumed for illustration to be of one and one-half inches 50 diameter, has to be reamed out with a bar one inch or more in diameter after the finished charge is removed from the converter, an opening with a minimum diameter of about one and five-sixteenths inches is required in the body of the tuyère valve, which opening is only partly filled therefore by

the shank of the punch rod. Consequently, when the rod is inserted and the valve is lifted from its seat, a blast of air escapes around the shank of the rod. As the rod is 60 withdrawn from the molten charge the escaping air is filled with a shower of sparks or bits of red hot metal, a circumstance which makes the duty of the "puncher" at 65 the present time a disagreeable one and decidedly dangerous unless he is well protected by leather apron, gloves and goggles. Furthermore, compressed air is wasted, and the consequent lowering of the pressure in 70 the tuyère renders the punching operation 75 less effective than if it were accomplished under full pressure.

The object of the present invention is to provide means for preventing the escape of compressed air during the punching operation, thereby eliminating the disadvantages and dangers attending this operation as conducted at present.

The aforementioned object is accomplished by the provision of means between 80 the usual tuyère valve and the operator or "puncher" for engaging the punch-rod to close off the passage which otherwise would exist between the rod and the tuyère tube due to the difference in their diameters, as 85 previously explained. The means referred to is in effect a sort of auxiliary valve, and preferably it acts automatically upon introduction of the punch rod to close upon the shank of the same. If automatic, it is preferably 90 of a yielding or expandible type, and so constructed and arranged as to fit closely about the shank of the rod and yet permit ready passage therethrough of the upset end of the punch rod during entry or withdrawal of the rod.

Having thus referred briefly to the objects and general construction of my invention, I shall now describe more particularly, and for a fuller understanding of its principle and scope, one embodiment of the improvements, referring for this purpose to the accompanying drawings wherein:

Fig. 1 is a vertical sectional view, partly broken away, of a conventional converter 105 having my improvements applied thereto;

Fig. 2 is a vertical sectional view on a somewhat larger scale than Fig. 1 showing a tuyère embodying one form which the present improvements may take, and also 110 showing a punch rod of conventional type in position to be introduced into the tuyère;

Fig. 3 is a front elevation of the auxiliary valve housing as viewed from the left in Fig. 2, part thereof being broken away;

Fig. 4 illustrates in perspective a preferred form of valve;

Fig. 5 shows in perspective a detail of the valve;

Fig. 6 is a vertical sectional view of the valve with modified means for attaching the 10 valve casing in place; and

Fig. 7 is a sectional view showing the embodiment of the invention used in connection with a second type of tuyère valve, and also showing another manner of securing 15 the auxiliary valve casing in place.

In the drawings, the numeral 10 indicates a converter of conventional form having a wind-box 11, supplied with air in customary manner from a main, not shown, 20 which similarly supplies air to all of the tuyères of the converter. The wind-box 11 communicates with the tuyère 12 through a passage 13. The tuyère pipe 14 is secured to the rear of the tuyère and passes through 25 the jacket and lining of the converter to the interior of the same and a slight distance into the charge. The tuyère is shown fixed in position against the wind-box by means of a supporting bracket 15 and adjustment 30 screw 16. A tuyère valve 17, shown in Figs. 1 and 2 as an inwardly swinging flap-valve having a sphere-segment protuberance 18 on its outer cheek, closes the port 19 in the fore-wall of the tuyère, through which port 35 the punch-rod 20, Fig. 2, having an upset head 21 may be introduced periodically to open up the tuyère pipe 14 in the well known manner. Referring to Fig. 2, the front plate or block 22 of the tuyère may 40 be secured to the latter by means of screw-bolts 23 passing through eyes 24 in the plate or flanges thereon. The eyes 24 are slightly larger than the diameter of the bolts so that the plate 22 may be centered properly before 45 tightening the bolts 23. The valve 17 is shown pivoted on a pin 25 carried in the squared head 26 of a screw-bolt 27 which threads into the block 22 from the rear side thereof.

I shall now proceed to describe those parts which are related more directly to my improvements. Beyond the tuyère valve 17, that is, on the opposite side of the tuyère valve from the tuyère box 28, is secured an assembly of cooperating elements arranged about the port or passageway 19, through which the punch rod 20 is introduced, in such manner as to close upon or be closed upon the shank of the rod when 50 the upset end thereof is entered so far as to open partly or wholly the tuyère valve 17. In its preferred form the assembly, as shown in detail in Figs. 2, 4 and 5, comprises a number of interlocking or overlapping plates or sections 29, four such sections

being illustrated, and each being roughly of quadrant shape, the series matching, when closed upon one another as shown in Fig. 4, to form a spool-like body having flat sides, an open center or eye 30 and a peripheral groove 31. This is attained by shaping the plates as shown in Fig. 5, wherein it will be seen that a portion, say 30°, of the opposite ends of the sides of each section is cut away to the central plane 75 as indicated at 32 to receive the corresponding shoulder of the next adjacent plate. By this arrangement the lines of division break joint with one another and there is no direct path for possible leakage axially across the 80 assembly. Each section is bevelled centrally at 33 on one side and at 34 on the other, a relatively narrow flat portion or throat 35 being left cylindrical. A groove is formed in each section so that when assembled the 85 continuous peripheral groove 31, Fig. 4, is provided. The eye 30, when the plates or sections are entirely closed upon one another and when the eye is therefore of smallest 90 diameter, should not be greater than the diameter of the shank of the punch rod 20 and preferably is of the same diameter, although it may be smaller.

Referring to Fig. 2, it will be seen that the assembled sections are held in contact 95 axially by engagement on one side with the outer wall 36 of the block 22 and on the other side with the inner face 37 of a housing or casing 38 which is removably secured to the block 22 or fore-wall of the 100 tuyère in a manner presently to be described. The casing 38, shown in front elevation in Fig. 3, is provided with an opening 39 in alignment with the port 19 of plate 22 and it may be flared as at 40 to 105 facilitate entry of the punch rod head 21. The port 19 of the block 22 may similarly be flared as indicated at 41.

An endless spiral spring 42 in the peripheral groove 31 encircles the plate-sections 110 29 and yieldingly presses them radially inward toward the maximum position of interlocking relation. The sections 29 fit fairly snugly in the space between the two walls 36 and 37 so as to prevent material 115 leakage of air past the same, but the fit is not so close as to interfere with the radial movement of the sections under the action of the spring or when spread apart by the punch rod.

With the form of assembly just described it is desirable to enclose the same in a housing such as casing 38 previously described. If the elements of the assembly are moved into or out of rod engaging position by 125 hand, the casing 38 may of course be modified somewhat or omitted altogether if desired, any suitable means being employed to support the assembly against the front 120 of the tuyère with its center in alignment 120

with the entrance to the tuyère and the tuyère pipe. When a casing is employed it may be removably attached to the tuyère in any suitable manner. As indicated in 5 Figs. 2 and 3, the casing is attached in the following manner: The foreblock 22 of the tuyère is formed or provided along the periphery of its outermost portion with two flanges 43, each of which may extend over 10 an arc of say 90°, leaving opposed arcuate open sections 44, in the instance mentioned, extending also over arcs of 90° each. The rear of the casing 38 is formed or provided with a pair of inwardly turned lips 45, each 15 of which extends over an arc not greater than that of the spaces between the flanges 43. Between these lips arcuate spaces are left which will be sufficiently long to permit passage therethrough of the opposed 20 flanges 43. The distance of the inner walls 46 of the lips 45 from the rear face 47 of the casing is such as to receive snugly the flange sections 43 upon relative rotation of the casing 38 and the block 22 when the 25 lips 43 have passed through the arcuate spaces between the flanges 45; and in order to bind the parts in assembled position the walls 46 of the lips and (or) the contacting sides of the flanges 43 may be formed 30 with shallow cam surfaces in a manner well understood in the metal-working arts.

The use of the above described improvements will be apparent from Fig. 2. As the punch rod 20 is introduced into the tuyère 35 the upset head 21 thereon will ride upon the bevelled surface 33 of the expandible ring or spool and force the sections 29 apart against the tension of the resilient restraining means 42 until the eye of the ring is 40 sufficiently large to permit the passage of the punch rod head 21. After the latter has passed through the eye the sections 29 are immediately pressed inwardly to close tightly upon the shank of the punch rod. Further 45 movement of the punch rod opens the tuyère valve 17 and the punch rod may then be moved across the tuyère into and through the tuyère pipe 14 in the customary manner.

50 It will be seen that so long as the valve 17 is held wholly or partly open by the punch rod, escape of air from the tuyère through the annular space between the rod and the inner wall of the block 22 is prevented by the auxiliary valve which I provide. Upon withdrawal of the punch rod the bevelled rear side of the upset head 21 will cause it to be guided and centered by the inclined surface 34 of the expandible 55 ring and the head will force the sections 29 apart just as in the case of its introduction; the tuyère valve 17 has closed in the meantime.

In Fig. 6, the casing 38^a is hinged at 48 60 to a flange formed for that purpose on the

plate 22^a, and at the bottom is secured by a suitable latch 49.

In Fig. 7, the casing 38^b is provided with an internal thread 50 which engages a corresponding male thread on the plate 22^b. 70 Also, the tuyère valve arrangement in this figure is of the well known Dyblie type comprising a ball 51 and a run 52; while the hinged valve shown in Figs. 1 and 2 is of the well known Shelby type. 75

In casings requiring rotative movement thereof with respect to the fore-plate of the tuyère for attachment, as illustrated in Figs. 2 and 7, the casing may be provided with a polygonal extension such as the hexagonal 80 nut 53 for application of a wrench.

While I have shown and described a preferred embodiment of my invention, it will be obvious that in its broader aspect the means employed to attain the desired result 85 may be widely varied. For example, it will be apparent that the elastic means for pressing the plate sections inwardly against the shank of the punch rod need not be integral; in fact spring-members whether integral or of separate pieces may be dispensed with if it is not deemed necessary that the action of the plates be automatic, and the overlapping plate sections may in 90 such case be spread or closed or both, by hand, for instance in a manner analogous to that common in the use of well known iris shutters for cameras; and the plates may be housed or not. Other obvious variations of certain of the details illustrated 95 may of course be introduced without departing from the invention in its broader scope; and the appended claims are to be construed specifically only in so far as the elements referred to in the respective claims 100 are specifically described therein.

I claim:—

1. In combination with a tuyère provided with means affording entry therethrough of a punching tool, means closable upon the 110 shank of the tool to prevent escape of fluid from the tuyère when the tool is inserted.

2. In combination with a tuyère provided with means affording entry therethrough of a punching tool, means automatically closable upon the shank of the inserted tool to prevent escape of fluid from the tuyère. 115

3. In combination with a tuyère provided with means including the usual tuyère valve affording entry of a punch rod through the tuyère, an auxiliary valve closable upon the shank of the rod to prevent escape of fluid 120 from the tuyère when the tool is inserted.

4. In combination with a tuyère provided with means including the usual tuyère valve affording entry of a punch rod through the tuyère, an auxiliary valve automatically closable upon the shank of the inserted rod to prevent escape of fluid from the tuyère. 125

5. In combination with a tuyère provided 130

with means affording entry therethrough of a punch rod of the type having an upset end, an expandible valve automatically closable upon the shank of the inserted rod to 5 prevent escape of fluid from the tuyère, said valve being expanded by engagement therewith of the upset end of the punch rod upon entry or withdrawal of the latter.

6. In combination with a tuyère provided 10 with means affording entry therethrough of a punching tool, a series of co-operating plates arranged about the path of travel of said tool and adapted to contact along their inner edges with the shank of the tool, there- 15 by providing a closure about the inserted tool to prevent escape of fluid from the tuyère.

7. In combination with a tuyère provided with means including the usual tuyère valve 20 affording entry of a punch rod through the tuyère, a casing on the forward portion of the tuyère, a series of plates within said casing in advance of said valve and arranged radially about the path of travel of said rod 25 in a plane transverse of the tool and adapted to contact along their inner edges with the shank of the rod, and yieldable means tending to maintain said plates in contact with the rod when inserted, said plates co-operat- 30 ing and forming with said casing an auxiliary valve to prevent escape of fluid from the tuyère around the rod.

8. In combination with a tuyère provided with means including the usual tuyère valve 35 affording entry of a punch rod through the tuyère, a casing in front of the tuyère, a series of plates within said casing and arranged radially about the path of travel of said rod in a plane transverse of the tool, 40 the inner edges of the plates being adapted to contact with the shank of the rod when the latter is inserted, and forming an eye through which the rod is introduced, and yieldable means tending to maintain said 45 plates in contact with the rod, said plates co-operating and forming with said casing an auxiliary valve to prevent escape of fluid from the tuyère.

9. In combination with a tuyère provided 50 with means affording entry therethrough of a punching tool, a series of overlapping, substantially sector-shaped plates arranged radially about the path of travel of said tool in a plane transverse of the tool and 55 adapted to contact along their inner edges with the shank of the tool, thereby providing a closure about the inserted tool to prevent escape of fluid from the tuyère, and yield- 60 able means for applying centrally directed pressure on the plates.

10. In combination with a tuyère provided 65 with means affording entry therethrough of a punch rod, a series of substantially sector-shaped plates arranged about the path of travel of said rod, each

plate having a portion of each of its sides reduced to afford interfitting and overlapping contact of adjacent plates, and elastic means for maintaining the plates in yielding contact along their inner edges with the 70 rod when inserted, thereby preventing escape of fluid from the tuyère.

11. In combination with a tuyère pro- 75 vided with means affording entry therethrough of a punch rod, a series of sub- stantially sector-shaped plates arranged about the path of travel of said rod, each plate having a portion of each of its sides reduced to afford interfitting and overlapping contact of adjacent plates and grooved 80 along its circumference so that when as- sembled a continuous, peripheral groove is provided about the assembly, and a spring in said peripheral groove for maintaining the plates in yielding contact along their 85 inner edges with the rod when inserted, thereby preventing escape of fluid from the tuyère.

12. In combination with a tuyère pro- 90 vided with means including the usual tuyère valve affording entry of a punch rod through the tuyère, a casing for attachment to the tuyère and having an opening adapt- 95 ed to register with the tuyère opening, a series of substantially sector-shaped plates in said casing about the opening in said cas- ing, each plate having a portion of each of its sides reduced to afford interfitting and overlapping contact of adjacent plates and 100 grooved along its circumference so that when assembled a continuous, peripheral groove is provided about the assembly, the assembly having slidable contact along its opposite sides with the interior of said cas- ing, and a spring in said peripheral groove for maintaining the plates in yielding contact along their inner edges with the rod when inserted, said plates co-operating and 105 forming with said casing an auxiliary valve 110 to prevent escape of fluid from the tuyère.

13. An attachment for converters or the like having tuyères through which a punch rod is introduced, comprising a casing removably attachable to the tuyère, and means 115 within said casing for yieldingly engaging the rod and co-operating with said casing to intercept the passage of air from the tuyère along the rod.

14. An attachment for converters or the like having tuyères through which a punch rod is introduced, comprising a casing hav- 120 ing an interrupted thread adapted to en- gage a corresponding thread on the tuyère for detachably securing said casing on said tuyère, and means within said casing for yieldingly engaging the rod and co-operat- 125 ing with said casing to intercept the pas- sage of air from the tuyère along the rod.

In testimony whereof, I affix my signature.
PER ALEXANDER FAUST.
